UNITED STATES PATENT OFFICE.

JASPER BLACKBURN, OF KIRKWOOD, MISSOURI.

TRAIN-PIPE COUPLING.

1,106,619.

Specification of Letters Patent. Patented Aug. 11, 1914.

Application filed February 1, 1913. Serial No. 745,619.

To all whom it may concern:

Be it known that I, JASPER BLACKBURN, a citizen of the United States, and resident of Kirkwood, St. Louis county, Missouri, 5 have invented certain new and useful Improvements in Train-Pipe Couplings, of which the following is a specification containing a full, clear, and exact description, reference being had to the accompanying 10 drawings, forming a part hereof.

My invention relates to improvements in train pipe couplings, and the primary object of my invention is to construct train pipe couplings in which the train pipe terminals extend at right angles to the line of impact, and to construct at least one of each 15 pair of the coupling-members with a jaw movable in a direction at right angles to the line of impact and spring-held to seat 20 against the train pipe terminal of an adjacent car.

A further object of my invention is to construct train pipe couplings arranged to connect a plurality of train pipes and to 25 provide means for selectively connecting a given train pipe on one car with a like train pipe on an adjacent car, regardless of the arrangement of the train pipes on any car.

A further object of my invention is to 30 construct companion train pipe coupling-members in such manner that one coupling member may be rigidly secured to one car and its companion member flexibly secured to another car yet arranged to be rigidly 35 held in the first mentioned coupling-member, the two coupling-members constructed to automatically compensate for both lateral and vertical variances of car alignments.

With the above purposes in view my in- 40 vention consists in certain novel features of construction and arrangement of parts which will be hereinafter more fully described, pointed out in the claims and set forth in the accompanying drawings, in 45 which—

Figure 1 is an elevation showing portions of the sub-structures of two cars equipped with train pipe couplings constructed according to my invention; Fig. 50 2 is a central longitudinal sectional elevation of companion coupling-members in a coupled position, the supports for the

coupling-members being broken away; Fig. 3 is a sectional plan taken on the line 3—3 of Fig. 2; Fig. 4 is a transverse sectional elevation taken on the line 4—4 of Fig. 2; Fig. 5 is a plan of the two coupling-members, as shown in Figs. 2 and 3, a portion of the one member being broken away and illustrates the lateral compression springs 60 for the movable jaws; Fig. 6 is a plan of the flexible coupling-member partly broken away and partly in section and illustrates the springs which automatically center the flexible head; Fig. 7 is a transverse sectional elevation through the two coupling-members in a partly coupled position showing the construction which prevents frictional wear of the gaskets; and Fig. 8 is an inverted plan showing my improved 70 train pipe coupling members and their positions relative to a car which is shown by dotted lines.

Referring by numerals to the accompanying drawings: 10 and 11 indicates the sub- 75 structures of two railway cars.

12 and 13 designate the draw bars which are carried respectively by the structures 10 and 11. Depending from the draw bars 12 and 13 are the hangers 14 and 15 and 80 secured to each of the hangers is a pair of train pipe coupling-members, each pair comprising a rigid coupling-member 16 and a flexible coupling-member 17. In this connection it is to be understood that a car 85 fully equipped with my train pipe coupling apparatus has at each end a pair of coupling-members, one a rigid member and the other a flexible member, thus each car fully equipped has four coupling-members. Each 90 of the coupling members 16, designated the rigid coupling-members, comprises a stem 18 which is secured to the hangers 14 by means of bolts 19. At the forward end of the stem 18 there is formed a socket 20 having the forwardly projecting arms 21 which constitute a furcated continuation of the stem 18. The inner margins of the arms 95 form continuations of the upper and lower faces of the socket 20. Formed integral 100 with the end of each arm 21 there is a relatively broad jaw 22 which will hereinafter be termed the "fixed jaw". The upper and lower margins of the socket 20 each has a

broad face 23 at right angles to the stem 18, and each of the fixed jaws 22 has a broad face 24 alining with and arranged to oppose the broad faces 23 of the socket. 5 Extending laterally and preferably formed integral with the arms 21 are the oppositely extended pairs of guide pins 25. Arranged for lateral movements upon the pins 25 are the movable jaws 26 which in transverse section, as shown in Fig. 4, are substantially U-shape and provided with transverse bores 27 which are arranged to receive the guide pins 25. Formed transversely through the upper and lower sides 10 of the movable jaws and through the arms 21 are openings arranged to receive the contractile coil springs 28 which normally tend to hold said jaws inwardly so that their inner faces are held to the arms 21. 15

20 Extended horizontally through each of the movable jaws 26 and on a median line thereof are the cavities 29, the outer forward ends of which terminate in gasketed orifices 30 which stand at right angles to the train line and which are the terminals of the train 25 pipes. Formed in each of the movable jaws surrounding the gasketed orifices are the concaved depressions 31. Extending forwardly of the said concaved depressions are 30 the outwardly flaring guides 32, in the inner faces of which are formed the channels 33.

In order that the movable jaws may be moved laterally with a minimum of friction, I have provided the rollers 34 and 35 which 35 engage respectively the broad faces 23 and 24 of the fixed socket and jaws. Carried by the movable jaws 26 there is a nipple 36 to which is secured a flexible hose section 37 having at its free end a hose coupling-member 40 38.

39 designates a train pipe which connects with a steam heating system, or an air brake system, or with an air signal system.

Each car fully equipped with my improved apparatus has four of the train pipes 39, each having at each end a flexible hose section 40 provided with the coupling-members 41 which connect with coupling-members, such as 38.

50 In the coupling-member 17, designated the flexible member, there is a stem 42 which is longitudinally slotted and secured to the hanger 15 by means of bolts 43 passing through the slots in order to provide for a 55 movement of the flexible coupling-member lengthwise relative to the car carrying it. Formed at the forward end of the stem 42 there is a vertical bore arranged to receive a hinge pin 44.

60 45 designates a metallic frame having on its rear face the hinge members 46 through which the hinge pin 44 passes, so that the frame may swing relative to the stem 42.

Extended rearwardly from the frame 45 65 are the flanges 47 each of which carries an

angularly disposed boss 48. Formed on the stem 42 to the rear of its hinge point and alining with the bosses 48 are the bosses 49.

50 designates contractile coil springs held in place between the pairs of bosses 48 and 70 49 and whose functions are to normally hold the frame in longitudinal alinement with the stem.

Extended forwardly from the frame 45 are the flanges 51 arranged one above the other and at the top and bottom of the frame. Extended through openings formed in the lowermost flanges 51 are the pipes 52, each of which has at its upper end a T-coupling 53. Secured to the T-couplings opposite the ends of the pipes 52 are the guide rods 54 which extend through openings formed in the uppermost flanges 51. Extended forwardly from each of the T-couplings 53 is a tubular coupling 55, and carried by the pair of couplings 55 is a head 56 which tapers from its rearmost end forwardly and inwardly, and is formed to accurately fit the socket and fixed jaws of the opposite or fixed coupling-member. Adjacent the rear of the head and on each side face thereof there is a gasketed orifice 57 which extends to the periphery of the convexed bosses 58 which, when the two coupling-members are coupled, seat in the concavities 31 of the movable jaws of the opposite coupling-member.

The gaskets in the concavities 31 and in the fixed bosses 58 each normally stands slightly beyond the faces of said concavities and said bosses, but by reason of the formation of the convexed bosses and the formation of the movable jaws, i. e., the channels 33 in the movable jaws, the gaskets in the head 56 will not engage the movable jaws during the act of coupling, so that there will be no wear of the gaskets by friction.

59 designates a coil spring embracing each of the pipes 52 and impinging between the T-coupling 53 and the lowermost flange 51 of the frame 45. These coil springs are arranged to normally hold the head 56 in about the same horizontal plane as the stem 42 of the flexible coupling-member.

In order that the pipes 52 and the guides 54 may be relieved from the longitudinal impacts I provide a pair of rollers 60 which are carried by the frame 45 to engage each of the pipes 52 and the guide rods 54.

61 designates a roller carried by the T-coupling 53 and arranged to engage the forward flat face of the frame 45.

For the reason that the coupling of the various train pipes is alike in each instance, 125 I will describe only the practical operation of a single train pipe coupling. When two cars, which are equipped with my improved train pipe coupling-members, are brought together, the head of the flexible member is 130

brought into engagement with the jaws of the fixed member and expands or spreads apart the movable jaws of the fixed member, the impact being sufficient to fully seat the head of the flexible member into the socket of the fixed member, at which point, that is the final seating point, the gasketed orifices or the terminals of each train pipe register, and the contractile springs acting upon the movable jaws of the fixed members draw the gaskets of the fixed jaws to a fluid tight connection with the gaskets of the flexible member.

It is to be observed that in coupling, the impact of the coupling is at right angles to the gaskets so that the gaskets are not deteriorated by the impacts. It is to be observed further that, by reason of the clearance in the guides of the movable jaws, the gaskets are moved without friction through the movable jaws, so that there is no frictional wear of gaskets.

By reason of the flexible hose connections referred to I may connect a car equipped with my coupling-members to a car having the ordinary hose coupling devices.

By reason of the fluid tight connections between the train pipe terminals being made at right angles to the trend of the cars the gaskets at the train pipe terminals are relieved from all of the wear by impacts in coupling.

I claim:

1. In combination with a train pipe coupling member having laterally movable elements, each of which is provided with a train pipe terminal, a second coupling - member provided with train pipe terminals arranged to register with the pipe terminals in the first mentioned member, the terminals of each member standing substantially at right angles to the trend of the cars, and guides on each of said coupling-members.

2. In a train pipe coupling, a coupling-member having fixed opposing jaws and opposing jaws movable at angles relative to the trend of a car, each of said movable jaws being provided with a train pipe terminal, and means acting on each of said movable jaws for moving them in given directions at right angles to the trend of the car.

3. A train pipe coupling, comprising a coupling - member, means for securing the coupling - member to a car, opposed fixed jaws, a socket at the base of the jaws, opposed jaws movable at right angles to the trend of the car, there being train pipe terminals in each of the movable jaws, a second coupling-member comprising a frame, means for mounting said frame on a car so that it may have longitudinal as well as lateral movements relative to the car, a tapering head carried by said frame and mounted so that it may be moved vertically relative to the frame, and there being train pipe terminals in said head arranged to register with the train pipe terminals in the first mentioned coupling-member.

4. In combination with a train pipe coupling-member provided with fixed elements containing train pipe terminals, a second train pipe coupling-member having laterally yielding elements containing train pipe terminals, means on the first mentioned coupling - member for spreading the elements containing the train pipe terminals on the other coupling-member so that the train pipe terminals of the two coupling-members may be brought to registration, and means acting on said movable elements containing the train pipe terminals for forcing the train pipe terminals into fluid tight connection.

5. In combination with a train pipe coupling - member having opposed fixed jaws and opposed jaws movable in a direction at right angles to the trend of the car, there being depressions in said movable jaws and gasketed train pipe terminals located in said depressions, a second coupling-member comprising a tapering head arranged to act on said movable jaws of the first mentioned member to spread them, there being bosses at the rear end of the head arranged to fit the depressions in the movable jaws of the other coupling-member, gasketed train pipe terminals carried by said bosses, and means for supporting said head so that it may accommodate itself automatically to lateral and vertical differences in the alinement of the first mentioned coupling-member.

6. A train pipe coupling, comprising a fixed coupling-member having laterally movable elements containing train pipe terminals, a flexible coupling - member carrying a head arranged to operate the movable jaws of the first mentioned member when moved lengthwise relative thereto, there being train pipe terminals carried by said head arranged to register with the train pipe terminals of the first mentioned coupling - member, and means acting on said movable jaws for holding the train pipe terminals when registered to fluid tight connections.

7. A train pipe coupling-member, comprising a stem arranged to be rigidly secured to a car, a pair of outwardly flaring fixed jaws formed integral with said stem and arranged one above the other, oppositely disposed laterally movable jaws, springs acting on said jaws to draw them in directions toward each other, there being gasketed orifices in each of the movable jaws, means for flexibly connecting each of the movable jaws with a train pipe, and channeled guides in each of the movable jaws in advance of the gasketed orifices.

8. A train pipe coupling - member, comprising a fixed support, a stem mounted for lengthwise movements relative to the support, a frame hingedly secured to the stem, 130

springs for holding the frame normally at right angles to the stem, a head, and means whereby the head may be supported by the frame which permit vertical movements of 5. the head relative to the frame, there being a train pipe terminal in said head.

In testimony whereof, I have signed my

name to this specification, in presence of two subscribing witnesses.

JASPER BLACKBURN.
